UNITED STATES PATENT OFFICE.

HENRY W. ALLEN AND GEORGE R. MEEKER, OF BROOKLYN, NEW YORK.

DESIGN FOR A GAME-BOARD.

40,945.

Specification for Design.

Patented Oct. 18, 1910.

Application filed July 23, 1909. Serial No. 509,238. Term of patent 14 years.

To all whom it may concern:

Be it known that we, HENRY W. ALLEN and GEORGE R. MEEKER, citizens of the United States, residing in the borough of Brooklyn, in the county of Kings and State of New York, have invented a new, original, and ornamental Design for a Game-Board.

The design is illustrated in the accompanying drawing and shows in the figure thereof a face elevation of the same.

We claim:

The ornamental design for a game-board, as shown.

HENRY W. ALLEN.
GEO. R. MEEKER.
